United States Patent Office.

CONRAD GEORGE, OF LIGONIER, PENNSYLVANIA

Letters Patent No. 65,899, dated June 18, 1867.

CHURN.

The Schedule referred to in these Letters Patent and making part of the same.

TO ALL WHOM IT MAY CONCERN:

Be it known that I, CONRAD GEORGE, of Ligonier, Westmoreland county, and State of Pennsylvania, have invented a new and useful Improvement in Churns; and I do hereby declare that the following is a full, clear and exact description thereof, reference being had to the accompanying drawings, and the letters of reference marked thereon, in which—

marked thereon, in which— Figure 1 is a perspective view of the entire churn, the sides being partly broken away to show the interior arrangement of the parts.

Figure 2 is a plan view.

Figure 3 is a side elevation of one of the dashers.

Figure 4 is a front elevation of the same.

Figure 5 is a longitudinal elevation of the partition; and

Figure 6 is a section of the same taken on the line x x of fig. 5.

Figure 6 is a section of the same, taken on the 1st July. Letters refer to like parts in all the figures.

Like letters refer to like parts in all the figures.
To enable others skilled in the art to make and use my invention, I will proceed to describe its construction and operation.

A is the churn-box, in which the slatted and perforated partition B is placed, which partition slides in vertical grooves cut into the front and back sides of the box, (as indicated in dotted outline at $r' s'$, in fig. 2,) so as to be removable. X X are the lids, resting in grooves on the top of the box A. C is the frame, in which the churn-box A is placed. D D are standards, firmly attached to the frame C, and stiffened by braces E E. These standards are provided with slots at their upper ends, to receive the cross-bar F, which is retained firmly in its place by means of removable pins c c. Fastened to the cross-bar F are standards G H I, which form supports and fulcra for levers, now to be described. The working-lever J has its fulcrum at d, in the standard H. The secondary levers K L are attached to the standards G I by the fulcrum-screws e f. To these levers are fastened the dasher-rod M N, by means of movable pins g h. The partition B is provided, at the bottom, with holes b' b', and slits c' c' at the top, which slits are bevelled from both sides, as shown in figs. 5 and 6. The milk is churned by being forced through the holes in both the partition and the dasher-valves by the reciprocating motion of the dashers. This reciprocating motion causes it to flow back and forth through the slits, which collect the particles of butter, as fast as they are formed, in two rolls, one on each side of the partition. It is admitted to the levers K L by the movable pins g h, which are admitted to the standards G I by the pins e f.

The operation of the churn is as follows: Motion being given to the lever J, it is transmitted to the levers K L, by means of the screws or pins *i j* working in slots *k l*, (the levers K L being of the third order.) This arrangement of levers not only gives an alternating motion to the dashers, but increases their throw, without increasing their distance apart—a very important circumstance, as upon it depends much of the compactness, convenience, and efficiency of the churn. The lower ends of the rods M N are constructed with broad bearing-plates *m m*, into which are let the transverse bearing-strips O O and P P, between which are hung perforated dasher-valves R R and S S, which vibrate on the pivots *y y* and *z z*. The strips O O and P P are provided with ledges, *q q* and *r r*, formed so as to prevent the valves R R and S S from opening upward beyond a horizontal position, as shown in red outline in fig. 3, the normal position of the valves being shown in black in the same figure. As the dashers work up and down alternately, the valves R R and S S, in the descending dasher, are forced up by the action of the milk to a horizontal position, (as shown in the said figure in red,) the milk being, at the same time, forced through the perforations in the dasher-valves R R and S S, and through the perforated bottom of the partition B. When the dasher has completed its downward stroke, and is rising, these valves are forced back to their former position by the weight of the superincumbent milk and their own gravity. Thus the dasher-valves rise and fall alternately, as the dashers are forced up and down in the act of churning. The object of the slotted rack or comb, in the upper portion of the separating board or partition B, is to collect the butter as fast as it is formed. The particles floating upon the surface of the milk, and flowing back and forth alternately through these bevelled slits, are gathered and collected on each side of the slats in two rolls or masses, which, when the churning is completed, are removed with great ease, leaving no small particles remaining in the milk, as is usual in other churning, but collecting it all together, even to the smallest particles.

In taking this churn apart to clean it, after use, take off the lids X X, take out the pins C C, and lift off the system of levers, with the dasher-rods and dashers attached. The dashers are then removed from the levers, and all the parts are in convenient form for cleaning and drying—a very essential matter in all dairy utensils.

Having thus described the construction and operation of my invention, what I claim, and desire to secure by Letters Patent, is—

1. I claim the combination of the double alternating levers J K L, and the partitioned churn-box A, all arranged substantially as and for the purpose set forth.
2. I claim arranging the levers J K L in a diagonal position, as shown, for the purpose of bringing the working ends of the levers K L over the centres of the churn divisions A A', as and for the purpose set forth.
3. I claim the combination of the perforated dashers, provided with the valves R R and S S, having the movements described, with the partition B, furnished with the holes b' b', and bevelled slits c' c', substantially as and for the purpose set forth.

CONRAD GEORGE.
